GARMENT HANGER

Julian Anderson, Helena, Mont.

Application June 13, 1947, Serial No. 754,373

1 Claim. (Cl. 223—93)

1

This invention relates to an improved construction of garment hanger especially adapted for use in check rooms for providing means whereby all of the garments left by a customer may be retained together and supported by a single hanger.

It is the customary procedure in check rooms to provide checks, each containing two sections which are correspondingly numbered. The customer is given one check and the other check is ordinarily retained with the coat left by the customer and the hat, overshoes or other check items are stored separately. In returning the checked garments, the check room operator is required to rely upon the customer for identification of the hat, overshoes or other garments than the coat, which not only results in delay but which also frequently results in mistakes, so that customers fail to receive their hats or other garments, which are not retained with the coat.

Accordingly, it is a primary object of the present invention to provide an improved garment hanger which is so constructed that a coat and hat, overshoes or other garments may be checked together and supported by a single hanger to enable all checked garments to be quickly regained and without danger of loss.

Various other objects and advantages of the invention will hereinafter become more fully apparent from the following description of the drawing, illustrating a preferred embodiment thereof and wherein—

Figure 1 is a front elevational view showing the improved garment hanger in use.

Figure 2 is a transverse sectional view taken substantially along a plane as indicated by the line 2-2 of Figure 1 and

Figure 3 is a longitudinal sectional view taken substantially along a plane as indicated by the line 3-3 of Figure 1.

Referring more specifically to the drawing, the improved garment hanger in its entirety is designated generally 5 and is formed from a body member of any suitable material, such as metal, designated generally 6 and which includes an elongated portion having correspondingly shaped ends 7 forming shoulder supporting elements. The intermediate portion of the body 6 is provided with an upwardly projecting extension 8 which is recessed to form a hook 9.

The body portion 6 is also provided, intermediate of its ends, with a depending projection 10 to the forward side of which is attached a lever or clip jaw 11 which is pivotally sup-

ported relatively to the portion 10 by a spring 12.

As best seen in Figure 2, the spring 12 has a coiled intermediate portion disposed on the forward side of the portion 10 and which engages behind an intermediate portion of the lever or jaw 11. One leg 14 of the spring 12 extends from one end of the coiled portion 13 downwardly and through the body portion 10 and has a terminal 15 bent so as to engage against the backside of said body portion 10 for securing the spring 12 thereto. The other end 16 of the spring 12 extends from the opposite end of the coil 13 diagonally across the jaw 11 and has its terminal portion 17 turned in the opposite direction for engaging across the outer side of the jaw or clip lever 11, adjacent its lower end and for urging said end yieldably against the body portion 10, which thereby constitutes the other, fixed jaw of a spring clip, designated generally 18.

20 One of the shoulder engaging portions 7 is provided with an elongated opening 19 which extends to adjacent the clip 18 and which affords an opening through which the fingers may be inserted for engagement with the backside of the body 6, so that pressure may be applied with the thumb against the upper end of the jaw 11 for opening the clip 18.

25

As clearly illustrated in Figures 2 and 3, the marginal edges of the body 6, including the hook 30 9 and depending extension 10, and the margin of the opening 19 are rolled rearwardly and outwardly to form rounded edges 20, in all portions of the hanger 5.

From the foregoing, it will be readily apparent that the clip jaw 11 may be opened, as previously described, for positioning a portion of a hat brim beneath the lower end thereof, as indicated in broken lines in Figure 1, after which, by releasing pressure on the upper end of the clip jaw 11, the lower end thereof will be moved inwardly by the spring 12, for clamping said portion of the hat brim between the clip jaw 11 and body portion 10. Likewise, a pair of galoshes, overshoes or other garment may be similarly attached to the clip 18. As indicated in broken lines in Figure 1, a coat may be hung in a conventional manner on the shoulder engaging portions 7 and will substantially enclose the hat or other garments supported by the clip 18, so as to protect said last mentioned garment from being crushed. Also, if desired, a handbag, umbrella, or similar article may be hung over the neck or upper extension 8. The hook 9 is adapted to be detachably engaged with a supporting hook or rod, not shown.

Various modifications and changes are contemplated and may obviously be resorted to, without departing from the spirit or scope of the invention as hereinafter defined by the appended claim.

I claim as my invention:

In a garment hanger of the character described, an elongated body member having end portions forming shoulder supporting elements for a coat or the like, said body member having a 10 depending intermediate portion, a spring pressed jaw carried by said depending portion and co-operating therewith to form a spring clip adapted to engage a hat or other garment and one of said end portions being provided with a finger receiv- 15

5

ing opening located adjacent said jaw whereby the fingers can be utilized for gripping the body portion of the hanger with the thumb disposed for opening the spring clip.

JULIAN ANDERSON.
